(57) **CLAIM**

The ornamental design for a handguard stabilizer, as shown and described.

DESCRIPTION

FIG. 1 is an isometric view of a handguard stabilizer showing my new design;

FIG. 2 is another isometric view of the handguard stabilizer shown in FIG. 1;

FIG. 3 is a front elevational view of the handguard stabilizer shown in FIG. 1;

FIG. 4 is a right side elevational view of the handguard stabilizer shown in FIG. 1;

FIG. 5 is a rear elevational view of the handguard stabilizer shown in FIG. 1;

FIG. 6 is a left side elevational view of the handguard stabilizer shown in FIG. 1;

FIG. 7 is a top plan view of the handguard stabilizer shown in FIG. 1;

FIG. 8 is a bottom plan view of the handguard stabilizer shown in FIG. 1; and,

FIG. 9 is an isometric view of the handguard stabilizer of FIG. 1 shown on a firearm handguard that forms no part of the claimed design.

The evenly spaced broken lines shown in FIGS. 1-9 depict portions of the handguard stabilizer that form no part of the claimed design. The long-dash/short-dash broken lines shown in FIG. 9 depict environment, specifically a handguard, that forms no part of the claimed design.

1 Claim, 6 Drawing Sheets
